US00D934247S

(12) **United States Design Patent** (10) **Patent No.:** **US D934,247 S**
(45) **Date of Patent:** **** Oct. 26, 2021**

(54) **KEYBOARD**

(71) Applicant: **SHENZHEN HONGTAIQI TECHNOLOGY CO., LTD.**, Shenzhen (CN)

(72) Inventor: **Qingbiao Zhang**, Shenzhen (CN)

(73) Assignee: **SHENZHEN HONGTAIQI TECHNOLOGY CO., LTD.**, Shenzhen (CN)

(**) Term: **15 Years**

(21) Appl. No.: **29/720,624**

(22) Filed: **Jan. 14, 2020**

(51) LOC (13) Cl. **14-02**

(52) U.S. Cl.

USPC **D14/392**

(58) **Field of Classification Search**

USPC ..... (57) **CLAIM**

The ornamental design for a keyboard, as shown and described.

DESCRIPTION

FIG. 1 is a front, right side, bottom perspective view of the keyboard showing my new design;

FIG. 2 is a rear, right side, top perspective view of the keyboard showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the keyboard that form no part of the claimed design.

1 Claim, 8 Drawing Sheets
